[57] CLAIM

The ornamental design for a toy digital watch substantially as shown and described.

DESCRIPTION

FIG. 1 is a perspective view of a toy digital watch showing my new design;

FIG. 2 is a top plan view;

FIG. 3 is an end view taken from the left end in FIG. 2;

FIG. 4 is a bottom view; and

FIG. 5 is a side elevational view.

The face of the watch shows different time when viewed from different angles.
